Primary Examiner — Derrick Holland*Assistant Examiner* — Lauren Calve*(74) Attorney, Agent, or Firm* — Harness, Dickey & Pierce, P.L.C.(57) **CLAIM**

The ornamental design for a cable and pipe penetration seal, as shown and described.

DESCRIPTION

FIG. 1 is top perspective view of a first embodiment of a cable and pipe penetration seal showing my new design;

FIG. 2 is a first end view thereof;

FIG. 3 is a first side elevational top view thereof;

FIG. 4 is a second end view thereof;

FIG. 5 is a second side elevational view thereof;

FIG. 6 is a top view thereof;

FIG. 7 is a bottom view thereof; and

FIG. 8 is a bottom perspective view thereof.

FIG. 9 is top perspective view of a second embodiment of a cable and pipe penetration seal showing my new design;

FIG. 10 is a first end view thereof;

FIG. 11 is a side elevational top view thereof, the opposite side being a mirror image thereof;

FIG. 12 is a second end view thereof;

FIG. 13 is a top view thereof;

FIG. 14 is a bottom view thereof; and,

FIG. 15 is a bottom perspective view thereof.
